CLAIM

The ornamental design for a stand for a collaborative electronic display, as shown and described.

DESCRIPTION

FIG. 1 is a front perspective view of a stand for a collaborative electronic display;

FIG. 2 is a front view of the stand of FIG. 1;

FIG. 3 is a back view of the stand of FIG. 1;

FIG. 4 is a first side view of the stand of FIG. 1;

FIG. 5 is a second side view of the stand of FIG. 1;

FIG. 6 is a top view of the stand of FIG. 1;

FIG. 7 is a bottom view of the stand of FIG. 1; and,

FIG. 8 is another front perspective view of the stand of FIG. 1 shown with a collaborative electronic display supported by the stand.

Any portions shown using dashed lines are for illustrative purposes only and form no part of the claimed design.

1 Claim, 8 Drawing Sheets
